WRAPPING MACHINE

Robert C. Wedge, Albert Lea, Minn.

Application May 6, 1935, Serial No. 19,933

22 Claims. (Cl. 93—2)

This invention relates to machines for wrapping relatively loose, irregular products such as plants, shrubs, bushes, etc., and while the invention is capable of use in several arts and for various purposes it is primarily designed for wrapping nursery plant stock that is to be shipped or stored until planted, and for that reason and for sake of convenience will therefore hereinafter be referred to and described as a plant or nursery stock wrapping machine only.

In the merchandising of plant stock it is found that invariably a considerable lapse of time occurs after the growing stock is removed from the ground and until it is shipped, sold, and replanted by the ultimate purchaser. During this interval, however, the stock must be maintained healthy and fertile, so as to not impair or retard its growing condition when replanted. To maintain the desired plant life condition it is necessary to keep the root portions moist and (in cold weather) warm, and it is therefore customary to wrap the root portion in moss or other moisture retaining material. To further insure retention of the moisture content the packing is enclosed in a moisture proofed cover, usually a tarred paper prepared for this purpose, and this cover is secured by cord, clips, paste, or other means.

To my knowledge the only means heretofore employed in thus wrapping nursery stock has been the manual or hand method, i. e., the operator places a sheet of the wrapping paper on a table, then after spreading a suitable amount of packing material on the paper, places the root end of the stock in the material, and then proceeds to roll the package together so that the cover encloses the packing and roots, after which the package is tied or otherwise secured and has the general appearance as indicated in Fig. 3 of the present drawings.

The manual method of wrapping plant stock just referred to, while quite universally employed, is unsatisfactory from several viewpoints. In the first place the method is very slow and does not produce uniform or entirely satisfactory results. Secondly it is impossible at least in many instances and where irregular root conditions prevail to produce a package that is sufficiently compact and tight to protect the roots and maintain the proper moisture conditions thereabout.

With the use of my machine, however, the operation is not only greatly speeded up, but the package is formed under motive power, thus insuring uniformity, compactness, and tightness,

and effects still further economy in that a smaller piece or sheet of the outer wrapper may be used than would be required in hand wrapping.

In the accompanying drawings, which illustrate a preferred embodiment of the invention:

Fig. 1 is a side elevation of the machine, with various parts in readiness to form a plant package, the right hand end of the machine as here shown being referred to for sake of convenience as the front end.

Fig. 2 is a top or plan view of the machine as shown in Fig. 1.

Fig. 3 is an elevation of a plant package as formed in and by the machine, a part of the cover paper being broken away for purpose of illustration.

Fig. 4 is an elevation similar to Fig. 1 but with the apron frame moved forward into operative position.

Fig. 5 is an enlarged detail sectional elevation through the wrapping mechanism but in an operative condition advanced from that shown in Fig. 4.

Referring to the drawings more particularly and by reference characters, 6 designates a frame work of a table or bench, having a top 7 upon which is performed the wrapping operation. The table structure includes a shelf 8, under the top 7, upon which is mounted a driving motor 9 and a speed reduction unit 10 through which power is transmitted to a shaft 11. The shaft 11 operates through a sprocket chain 12 and suitable sprocket gears 13 to drive a transversely extending shaft 14 journaled to the table frame 30 immediately below the top 7. At one end the shaft 14 is provided with a spur gear 15 for intermittent driving engagement with a spur pinion 16 which is adapted to be swung into and out of operative engagement with the gear as illustrated in Figs. 1 and 4. The shaft 14 is preferably journaled in bearing brackets 17 secured to the table, and which brackets have upward extensions in which are journaled the ends of a shaft or pipe 18 that is also parallel with but slightly spaced above the top 7.

The spur pinion 16 is secured upon one end of a shaft 19 that is journaled at its ends in arcuately curved side arms 20 of what may be generally described as a swingable apron frame 21 which is pivotally secured to the table frame 6 as at 22.

In addition to members 19 and 20 the frame 21 includes a rotatable shaft 23 and a cross bar 24 which not only serves as a manipulating han-

dle but also serves to rigidly connect the arms 20 so that they will swing in unison from the centers 22. The cross bar 24 may also rest upon a stop such as an upward projection of the table leg (see Fig. 1) to limit the rearward movement 5 of the apron frame and support it in proper initial operative position.

A flexible apron 25 extends over the top of the table as shown in Figs. 1 and 2, and one 10 end of this apron has its edge secured to the roller shaft 19 so that it may be wound thereabout when the shaft is rotated. This apron is preferably made of heavy durable canvas or duck and it may best be secured to the roller shaft 15 19 by extending it through a longitudinal slot therein, and then fixed to a heavy wire or bar within the shaft, which is hollow as shown in Fig. 5, to thereby positively secure and prevent accidental removal of the apron. Should the 20 apron become sufficiently worn or damaged it may be readily substituted by a new one by removing the shaft 19 and then slipping the apron end longitudinally outward through the shaft slot, whereupon a new apron may be resecured 25 by a reverse operation.

The opposite end of the apron is secured to and wound upon a roller 26 journaled in the table frame 6, as at 27, and one end of the roller has a pulley 28 over which operates the suspension cord 29 of a weight 30. The cord or rope 30 29 is of such length that when the weight 30 reaches and rests upon the floor the apron 25 will be in the slack position shown in Fig. 1. As soon as tension is applied to the apron, however, so as to roll it off from the roller 26 the weight will become operative to resist such unrolling action and keep constant tension on the apron.

When the machine is in use the motor 9 and 40 the driven parts 10, 11, 12, 13, 14, and 15 are moving continuously, and before the package is to be wrapped the apron frame 21 is in its rearward position, the weight 30 is resting on the floor, and the apron 25 is in the slack position 45 shown in Figs. 1 and 2. It should be noted that the apron extends over the roller 18 and passes over the shaft 22 to the shaft or roller 19.

The operator, standing at the rear end of the machine, now places a rectangular sheet of cover 50 paper 31 upon the apron 25 and at the place shown in Figs. 1 and 2. The front edge of the paper should project just over the roller 18 to secure the best results, and to the opposite edge portion of the sheet is applied an adhesive or 55 glue, such as indicated at 32, unless other securing means is to be employed.

The packing material 33 is now spread upon the rear part of the apron and the root end of the plant stock is placed upon the material so 60 spread, the top or branch ends projecting laterally outwardly, as shown. Thereupon the operator grasps the cross bar 24 with one hand and swings the frame 21 over and forwardly to the 65 position shown in Fig. 4, using the other hand if necessary to initially assist in the enfolding movement. The packing, stock, and enclosing apron portion will then assume the positions shown in said figure. The pinion 16 is now in operative engagement with the spur gear 15, and the shafts 70 18 and 23 are in the relative positions best shown in Fig. 5.

As rotating power is now applied to the shaft 75 19 the apron is wound up upon it and as this occurs the package enveloped by the looped apron is drawn or pulled in under pressure thus squeez-

ing the packing material closely in about the roots. When the desired maximum resistance is reached the shaft 19 continues to rotate but as it cannot further restrict the unit to be wrapped it revolves the unit within the apron 5 loop and pulls the apron rearwardly from the roller 26, and in doing so it also actuates into the loop the paper 31 which consequently becomes wrapped about the unit as shown in Fig. 5, at which time the adhesive 32 will secure the bundle 10 in its constricted condition. The bundle rolling action may be continued until the apron supply reaches its end or the weight 30 reaches its uppermost limit, at which time it is necessary to slightly raise the frame 21 to release the gear 15 connection. And a continued movement of the frame 21 rearwardly will of course discharge or release the bundle which can then be removed in the form shown in Fig. 3, although it is usually desirable to tuck in the lower end of the 20 wrapper, as indicated at 35.

The weight 30 now goes into action to rewind the apron back upon the roller 26 and off from the roller 19, whereupon the machine is in readiness for the next wrapping operation. 25

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A wrapping machine of the character described comprising a horizontal table support, an apron slideable longitudinally upon the support and upon which the object to be wrapped is placed, means for looping over the apron to inclose the object, and means for actuating the apron to restrict the loop thereof and thereby compress the object, said last mentioned means 40 being operative to slide the apron on the support when a predetermined degree of compression has been reached.

2. A wrapping machine of the character described comprising a table having a surface supporting a longitudinally movable apron upon one portion of which is placed an object to be wrapped and upon another portion of which is placed a cover sheet to inclose the article, means for looping the apron about the object, and means 50 for moving the apron longitudinally on the table surface to convey the cover sheet into the apron loop and wrap it about the object.

3. A wrapping machine of the character described comprising a suitable supported longitudinally movable apron upon one portion of which is placed an object to be wrapped and upon another portion of which is placed a cover sheet to inclose the article, means for looping the apron about the object, means operative upon an initial co movement to pull the apron from the loop to squeeze the object, and operative upon advanced movement to pull the apron longitudinally over the support and about the object to impart a rolling action thereto and move said cover sheet 65 into the apron loop and about the object. 55

4. The method of wrapping a plant stock or the like which comprises distributing packing material on a longitudinally movable apron, placing the root end of the stock on the distributed 70 layer of packing material, looping the apron to enfold the packing material about the stock, pulling the apron to apply squeezing pressure to the material about the stock to compress the same, rolling the resultant unit about a substantially 75

stationary axis while under squeezing pressure, and then applying and securing a cover sheet to the unit during the rolling movement and while still subjected to the squeezing pressure previously applied.

5. A wrapping machine of the character described comprising a suitable horizontal support, an apron extending over the top of the support, a roller at one end of the support and upon which one end of the apron is wound, a swingable frame at the other end of the support, a roller journaled in said frame and having the other end of the apron secured thereto whereby when the frame is swung over toward the first mentioned roller it will form a loop in the apron, and power actuated means for rotating the frame roller to constrict said apron loop and draw the apron from the first mentioned roller.

6. A wrapping machine of the character described comprising a suitable horizontal support, an apron extending over the top of the support, a roller at one end of the support and upon which one end of the apron is wound, a swingable frame at the other end of the support, a roller journaled in said frame and having the other end of the apron secured thereto whereby when the frame is swung over toward the first mentioned roller it will form a loop in the apron, and power actuated means for rotating the frame roller to constrict said apron loop and draw the apron from the first mentioned roller, said first mentioned roller having means tending to resist unrolling of the apron therefrom.

7. A wrapping machine of the character described comprising a suitable horizontal support, a frame pivotally secured to the rear end of the support for swinging movement forwardly, a motor, a roller journaled in the frame, means operative upon swinging the frame forwardly to establish driving connection between the roller and said motor, and an apron extending over the support with one end attached to the roller, so as to be wound thereabout under power from the motor when the frame is in its forward position.

8. A wrapping machine of the character described comprising a suitable horizontal support, a frame pivotally secured to the rear end of the support for swinging movement forwardly, a motor, a roller journaled in the frame, means operative upon swinging the frame forwardly to establish driving connection between the roller and said motor, an apron extending over the support with one end attached to the roller, so as to wind thereupon under motor power when the frame is in its forward position.

9. A wrapping machine of the character described comprising a suitable horizontal support, a frame pivotally secured to the rear end of the support for swinging movement forwardly, a motor, a roller journaled in the frame, means operative upon swinging the frame to a predetermined forward position to establish driving connection between the roller and said motor, and an apron extending over the support with one end attached to the roller, said support and frame having a pair of cooperating cross shafts between which overlapped portions of the apron pass when the frame is in its forward position.

10. A wrapping machine of the character described comprising a suitable horizontal support, a frame pivotally secured to the support for swinging movements to forward and rear positions, a roller mounted in one end of the frame, an apron extending over the support with one

end attached to the roller, a power driven gear member disposed at one side of the support, and a second gear member associated with said roller and adapted to intermesh with the first gear member when the frame is in its forward position.

11. A wrapping machine of the character described comprising a suitable horizontal support, a frame pivotally secured to the support for swinging movements to forward and rear positions, a roller mounted in the frame to swing therewith, an apron extending over the support with one end attached to the roller, a power driven gear member disposed at one side of the support, and a second gear member associated with said roller and adapted to intermesh with the first gear member when the frame is in its forward position, said support having a roller at its forward end to which the forward end portion of the apron is secured, and means tending to rotate the last mentioned roller to releasably wind the apron thereon.

12. A wrapping machine of the character described comprising a suitable horizontal support, a frame pivotally secured to the support for swinging movements to forward and rear positions, a roller mounted to swing with the frame, an apron extending over the support with one end attached to the roller, a power driven gear member disposed at one side of the support, and a second gear member associated with said roller and adapted to intermesh with the first gear member when the frame is in its forward position, said support having a roller at its forward end to which the forward end portion of the apron is secured, and a pulley, cord, and weight associated with the last mentioned roller to releasably wind the apron thereon.

13. A wrapping machine comprising a support, an apron extending over the top of the support and longitudinally slidab le thereon, a cross member disposed transversely of the support intermediate the ends thereof and under the apron, a roller near one end of the support and to which one end of the apron is secured for winding thereon, means tending to draw the apron over the support and unwind it from the roller, means for mounting the roller whereby it may be shifted forwardly to a position adjacent the cross member so as to form an enclosing loop in the apron, and means operative upon the roller reaching its forward position for rotating the same to constrict said apron loop.

14. A wrapping machine comprising a support, an apron extending over the top of the support and longitudinally slidab le thereon, a cross member disposed transversely of the support intermediate the ends thereof and under the apron, a roller near one end of the support and to which one end of the apron is secured for winding thereon, means tending to draw the apron over the support and unwind it from the roller, a shiftable frame movably mounting the roller on the support, and means operative upon shifting the frame to a predetermined position for establishing a power connection to the roller.

15. A wrapping machine comprising a support, an apron extending over the top of the support and longitudinally slidab le thereon, a frame movably mounted on the support, a roller in the frame and attached to one end of the apron whereby the latter may be wound thereon, said frame being shiftable to move the roller over the apron proper to produce an enclosing loop therein, a power actuated driving member carried by

the support, a driven member associated with the roller, said driving and driven members being operatively connected when the frame is shifted to the position producing said apron loop so as to rotate said roller and by winding the apron thereon to constrict said loop.

16. A wrapping machine comprising a support, an apron extending over the top of the support and longitudinally slidably thereon, a frame movably mounted on the support, a roller in the frame and attached to one end of the apron whereby the latter may be wound thereon, said frame being shiftable to move the roller over the apron proper to produce an enclosing loop therein, a power actuated driving member carried by the support, a driven member associated with the roller, said driving and driven members being operatively connected when the frame is shifted to the position producing said apron loop so as to rotate said roller and by winding the apron thereon to constrict said loop, and means operative upon reversing the movement of the frame to separate said driving and driven members to release the power applied to the apron.

17. A wrapping machine comprising a support, an apron extending over the top of the support and longitudinally slidably thereon, a frame movably mounted on the support, a roller in the frame and attached to one end of the apron whereby the latter may be wound thereon, said frame being shiftable to move the roller over the apron proper to produce an enclosing loop therein, a power actuated driving member carried by the support, a driven member associated with the roller, said driving and driven members being operatively connected when the frame is shifted to the position producing said apron loop so as to rotate said roller and by winding the apron thereon to constrict said loop, and means operative upon reversing the movements of the frame to release said power application to the apron roller and open said apron loop.

18. A wrapping machine comprising a support, an apron extending over the top of the support and longitudinally slidably thereon, a frame movably mounted on the support, a roller in the frame and attached to one end of the apron whereby the latter may be wound thereon, said frame being shiftable to move the roller over the apron proper to produce an enclosing loop therein, a power actuated driving member carried by the support, a driven member associated with the roller, said driving and driven members being operatively connected when the frame is shifted to the position producing said apron loop so as to rotate said roller and by winding the apron thereon to constrict said loop, and means operative upon reversing the movement of the frame to open the loop and unwind the apron from said roller.

19. A wrapping machine comprising a substantially horizontal support, a cross member extending over the support intermediate its ends, an apron extending longitudinally over the support and over the cross member, a roller at the fore end of the support to which one end of the apron is secured, yieldable means rotating the support to releasably wind the apron thereon, a roller at the rear end of the support and to which the other end of the apron is secured, a frame shiftably connecting the rear roller to the support

and permitting said roller to be swung to a position adjacent the cross member to form an enveloping loop in the apron, and means automatically connectable with the rear roller to rotate the same when the apron loop forming position thereof is reached to thereby constrict the loop and draw the apron rearwardly from the forward roller.

20. A wrapping machine comprising a substantially horizontal support, a cross member extending over the support intermediate its ends, an apron extending longitudinally over the support and over the cross member, a roller at the fore end of the support to which one end of the apron is secured, yieldable means rotating the support to releasably wind the apron thereon, a roller at the rear end of the support and to which the other end of the apron is secured, a frame shiftably connecting the rear roller to the support and permitting said roller to be swung to a position adjacent the cross member to form an enveloping loop in the apron, and means automatically connectable with the rear roller to rotate the same when the apron loop forming position thereof is reached to thereby constrict the loop and draw the apron rearwardly from the forward roller, said rotating means being rendered inactive when the frame is shifted to open the apron loop.

21. A wrapping machine comprising a substantially horizontal support, a cross member extending over the support intermediate its ends, an apron extending longitudinally over the support and over the cross member, a roller at the fore end of the support to which one end of the apron is secured, yieldable means rotating the support to releasably wind the apron thereon, a roller at the rear end of the support and to which the other end of the apron is secured, a frame shiftably connecting the rear roller to the support and permitting said roller to be swung to a position adjacent the cross member to form an enveloping loop in the apron, and means automatically connectable with the rear roller to rotate the same when the apron loop forming position thereof is reached to thereby constrict the loop and draw the apron rearwardly from the forward roller, said frame having a cross member adapted to engage the apron passing from the rear roller and cooperating with the cross member of the support in the forming of said apron loop.

22. A wrapping machine comprising a substantially horizontal support, a cross member extending over the support intermediate its ends, an apron extending longitudinally over the support and over the cross member, a roller at the fore end of the support to which one end of the apron is secured, yieldable means rotating the support to releasably wind the apron thereon, a roller at the rear end of the support and to which the other end of the apron is secured, a frame shiftably connecting the rear roller to the support and permitting said roller to be swung to a position adjacent the cross member to form an enveloping loop in the apron, and means automatically connectable with the rear roller to rotate the same when the apron loop forming position thereof is reached to thereby constrict the loop and draw the apron rearwardly from the forward roller, said rotating means including a radially separable pair of spur gears.
